UNITED STATES PATENT OFFICE.

MARGARET DUMONT, OF WACO, TEXAS.

CABINET.

Application filed April 18, 1925. Serial No. 24,250.

This invention relates to a cabinet for holding articles of food and the like, the general object of the invention being to make the cabinet portable so that it can be carried 5 by a motor vehicle and used for camping purposes as well as in a kitchen.

Another object of the invention is to provide a table which can be used in connection with the cabinet and which is foldable so 10 that it can be placed alongside the cabinet.

This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying drawings wherein like characters denote like or 20 corresponding parts throughout the several views, and in which:—

Figure 1 is a view showing the device placed on a running board of an automobile.

Figure 2 is a view showing the device set 25 up for use.

Figure 3 is a side view of Figure 2.

Figure 4 is a side view with the table in folded position.

Figure 5 is a rear view with the table in 30 set up position.

Figure 6 is a detail view showing one of the hook members on the cabinet.

Figure 7 is a detail view showing one of 35 the perforated ears on the table.

In these views, 1 indicates the cabinet which has its front provided with the doors 2 so that access can be had to the interior thereof and it has handles 3 on its sides so 40 that it can be easily carried from place to place. A vertical partition 4 is arranged in the cabinet and shelves 5 and a box 6 are placed in the spaces formed by said partition. Vertical strips 7 are placed in front 45 of the shelves to prevent articles from rolling off the shelves. The box 6 can be arranged to hold ice or other material. Thus it will be seen that the cabinet constitutes a kitchen cabinet for holding various articles.

50 A pair of hook members 8 are fastened to the top of the rear part of the cabinet with their upper parts projecting above the top with perforations 9 in these projecting parts so that the cabinet can be suspended from suitable supports. A table 10 is provided 55 with eyes 11 for engaging the hook members

8 so that one edge of the table will be supported by the cabinet and foldable legs 12 are hinged to the opposite side so that when the legs are swung downwardly the table top 60 will be held in horizontal position by said legs and the hook members on the cabinet, as shown in Figures 2, 3 and 5. When the legs are folded the table will assume a vertical position, as shown in Figure 4, at the 65 rear of the cabinet, though it will still be supported by the hook members 8. The legs are held in vertical position by the braces 13, each brace being composed of two links 14 which are pivotally connected together with 70 their outer ends hinged to the leg and table respectively. A lug 15 on one link engages a part of the other link to hold the parts in bracing position. Brackets 16 are arranged 75 on the bottom of the cabinet and these braces are adapted to receive the eyes 11 of the table when the cabinet is suspended from a wall or the like, to hold the table in set up position at the front of the cabinet. When the table is to be supported or arranged at 80 the front of the cabinet it will be understood that the cabinet must be a sufficient distance from the ground or other surface as to enable the legs 12 to hold the table top in horizontal position with the eyes 11 engaging the brackets 16.

From the foregoing it will be seen that I have provided a kitchen cabinet and a folding table which can be placed on the running board of an automobile, as shown in Figure 1, or which can be carried in any other kind of a vehicle so that it can be transported to the camping grounds and easily and quickly set up. The cabinet will provide a storage place for various articles of food and other articles as well as ice and the table after being set up can be used for various purposes, such as in the preparation of food and for 95 a dining table.

The doors of the cabinet should be made to fit dust and vermin tight and I prefer to form the ice box with two compartments, one for ice and one for food. When the device is hung on the wall it will take no floor space, thus making it desirable for small 100 kitchens and the like.

It is thought from the foregoing description that the advantages and novel features of my invention will be readily apparent.

I desire it to be understood that I may 110 make changes in the construction and in the combination and arrangement of the several

parts, provided that such changes fall within the scope of the appended claim.

What I claim is:—

5 A camper's outfit comprising in combination a cabinet, doors closing the front of the cabinet, spaced hook-like elements arranged vertically on the rear wall of the cabinet and having their corresponding upper ends projecting above the cabinet and provided with 10 openings whereby the cabinet can be suspended from an elevated support, a table top including foldable supporting legs, slotted plates secured to the under side of the table

top and projecting beyond one end thereof to receive said hooks when the cabinet is supported upon the ground with the table top projecting horizontally therefrom, and to permit said top to be folded at one side of the cabinet parallel therewith, and brackets depending from the bottom of the cabinet 20 and adapted to be engaged by said slotted plates to hold the table top associated with the cabinet when the latter is supported in spaced relation to the ground.

15

In testimony whereof I affix my signature.

MRS. MARGARET DUMONT.
